COVER FOR FIRE ALARM OR SIMILAR ARTICLE

David K. Walz, Stone Mountain, Ga., assignor to Orkin
Exterminating Company, Inc., Atlanta, Ga., a corpo-
ration of Delaware

Filed Mar. 8, 1968, Ser. No. 10,897

Term of patent 14 years

(Cl. D72—1)

FIG. 1

FIG. 2

FIG. 3

FIG. 4

FIG. 5

FIG. 6

FIG. 1 is a front elevation of a cover for a fire alarm or similar article showing one embodiment of my new design;

FIG. 2 is a typical side view of the design of FIG. 1;

FIG. 3 is a sectional view taken along line 3-3 in FIG. 1;

FIG. 4 is a front view of a modified form of my new design which has a side view substantially the same as that illustrated in FIG. 2; and

FIGS. 5 and 6 are sectional views taken along the lines 5-5 and 6-6 in FIG. 4.

I claim:

The ornamental design for a cover for fire alarm or similar article, substantially as shown and described.
